United States Patent Office

Des. 221,470
Patented Aug. 17, 1971

221,470

ICE CREAM DISPENSER

Sidney Sevell, 320 Wyoming Ave.,
North Massapequa, N.Y. 11758

Filed Apr. 8, 1970, Ser. No. 22,328

Term of patent 3½ years

Int. Cl. D7—99

U.S. Cl. D44—29

FIG. 1.

FIG. 2.

FIG. 1 is an isometric view of an ice cream dispenser showing my new design;

FIG. 2 is a bottom plan view thereof.

I claim:

The ornamental design for an ice cream dispenser, substantially as shown.
